COMPOUND CURLER

Nathan L. Solomon, Brooklyn, N. Y.

Application January 18, 1937, Serial No. 121,189

15 Claims. - (Cl. 132—33)

The present invention relates to hair curlers and is especially concerned with a compound hair curler wherein each end may be selectively and conveniently utilized as hair gripping and winding means and wherein each end selectively constitutes manipulating means for bodily rotating the compound curler about the longitudinal axis thereof. Specifically, however, the object of the invention is realized in the provision of a serviceable compound hair curler having an expanded portion and a reduced portion wherein the expanded portion is adapted to grip and wind the hair to be curled to form relatively large sized curlers upon the manipulation of the reduced portion and wherein the reduced portion is adapted to grip and wind hair to form relatively small sized curls upon rotation of the expanded portion. Other objects, advantages, features of the invention will be in part obvious and in part hereinafter specifically pointed out and for a clearer understanding of the invention attention is directed to the following detailed description considered in the light of the accompanying drawing in which:

Fig. 1 is a perspective view of the compound curler according to my invention, showing the reduced end gripping a tress of hair, while expanded end serves as a handle.

Fig. 2 is a perspective view of the compound curler wherein the expanded end serves to grip the hair and the reduced end constitutes the handle for winding the hair about the expanded end to form relatively large sized curls.

Fig. 3 is a sectional view taken on the line 3—3 of Fig. 1.

Fig. 4 is a longitudinal perspective view of the compound curler, showing the adjacent parts of the reduced portion closed or abutting and the enlarged parts of the expanded portion normally diverged.

Fig. 5 is a longitudinal sectional view of a modified form.

Fig. 6 is a sectional view on the line 6—6 of Fig. 5.

Fig. 7 is a longitudinal sectional view of another modification and

Fig. 8 is a sectional view on the line 8—8 of Fig. 7.

According to the invention the compound hair curler generally denoted 10 (Figs. 1—3 inclusive) comprises an elongated hollow body defined by the superimposed U-shaped sections broadly denoted 11 and 12 each of which includes an enlarged portion 13 from which integrally extends a reduced portion 14.

The superimposed enlarged portions 13 are provided with perforated ears 15 through which fulcrum pin 16 is first threaded and subsequently upset to form a rivet to prevent transverse rela-

tive displacement of the superimposed sections 11 and 12 and thus a hinged connection is provided to permit one of the U-shaped sections to be pivoted in respect to the companion section of the curler.

Cooperating with the enlarged portions 13 is a U-shaped spring 17 having its diverged legs 18 abutting opposing inner faces thereof to normally hold the enlarged portions 13 open or slightly diverged, defining gap 20, and to normally hold the superimposed reduced portions 14 closed or in abutting relation.

Where it is desired to form a relatively small curl, the superimposed portions 14 are utilized to first grip a portion of the tress to be wound and the enlarged portions 13 are utilized as a handle or manipulator for bodily rotating the compound curler about its longitudinal axis. In this connection the expanded part of the curler defined by the superimposed portions 13 is manually grasped to move the latter towards each other, thus separating or opening the attenuated or restricted part of the curler characterized by the superimposed reduced portions 14, however against the resistance of the legs 18 of the U-shaped spring 17.

Accordingly a suitable gap is formed by the attenuated part of the curler and consequently a free end of a tress 21 of hair may be interposed between the separated portions 14 as indicated in Fig. 1. Thereafter, finger pressure tending to hold the reduced portions apart is removed from the expanded part of the curler. It follows that spring 17 now acts to diverge the enlarged portions 13 and hence the terminal part of the tress is gripped by the reduced portions 14 which tend to close.

With the tress gripped within the restricted part of the curler, the handle constituted by the enlarged portions 13 is rotated, thus the tress of hair is wound about the reduced part of the curler, to form several superimposed convolutions and to remove the coiled hair, the enlarged parts 13 are pivoted slightly towards each other to remove the frictional grip on the tress by the reduced portions 14, and the curl formed may be slidably moved along the reduced part of the curler and outwardly therealong to be ultimately free thereof.

Where a relatively large curl is desired, the free end of the tress is first frictionally gripped in the gap 20 of the normally diverged enlarged portions 13 and the attenuated part of the curler defined by the superimposed companion parts 14 serve as a manipulating handle which is rotated to wind the tress in part gripped by the enlarged portions 13 about the latter. To remove the curl formed, the latter is grasped at one end and

slidably displaced until it clears the expanded part of the curler.

In the form according to Figs. 5 and 6 the compound curler comprises hingedly associated companion components 30 and 31. In the particular instance illustrated, component 30 is in the form of an elongated cylindrical tube having an enlarged part 32 and a reduced part 33' while component 31 defines an inverted U shaped cover characterized by an enlarged part 33 and a reduced part 34.

Depending from the cover are the spaced perforated ears 35 which straddle the sides of tube 30. Rivet 36 passing through the depending ears of the cover and the body of the tube and transversely thereof serves as fulcrum means to permit the cover to be pivoted in respect to the tube.

Arranged within the tube is a U shaped spring 37. This spring has one leg 38 abutting the bore of tube 30 and another leg 39 passing through opening 40 in tube 30 and abutting the inner surface of the enlarged part 31 of the cover, thus holding the latter normally separated from the tube to form a hair receiving gap 41.

In the separated open relation of expanded part 31, spring 37 acts to normally hold closed the attenuated part of the curler defined by the superimposed reduced parts 33' and 34 of the tube cover.

Where a large curl is to be formed, a portion of the tress is disposed in gap 41 and thus is firmly gripped in the expanded part of the curler. The attenuated or reduced part of the latter is thereafter utilized as a handle for winding the gripped hair about the expanded part of the curler.

If it is desired to form a relatively small curl, the reduced portions 33' and 34 are separated by moving the enlarged part 33 towards the enlarged part 32 to create a gap between the restricted parts of the tube and cover to receive a part of the tress of hair. Subsequently finger pressure is removed from the expanded part or actuator 33. It follows therefore, that the restricted part 34 due to the action of spring 37 moves towards its companion reduced part 33' of the tube and consequently the hair is appropriately gripped.

Thereafter, the enlarged or expanded part of the curler is rotated and the hair winds about the attenuated part thereof to form a small curl and to remove the latter, actuator 31 is depressed, and the curl formed may be conveniently and slidably removed from the reduced part of the curler as is well understood.

The compound curler shown in Figs. 7 and 8 is of the collapsible telescopic type. To this end it will be observed that expanded or enlarged tube 50 is provided with an elongated slot 51 for receiving and frictionally receiving a part of the tress to be wound. Tube 50 also includes a dome shaped portion 51' having an opening 52 for slidably guiding the reduced tube 53 having a hair receiving and gripping slot 54.

Integral with tube 53 is a flared end 55 which embodies a plurality of indentations 56 adapted to removably receive spring detents 57 struck out of the dome shaped portion 51'.

By this arrangement the reduced part of the curler may be interlocked with the expanded part thereof as illustrated in Figs. 7 and 8. In such relation, the expanded part of the curler may be used as the hair gripping and winding means and the reduced part thereof as the handle or the latter may be used as the hair gripping and wind-

ing means and the expanded part may be employed as the manipulator.

If it be desired to collapse the compound curler, the restricted part is rotated relative to the expanded part thereof, thus removing the detents 57 from indentations 56 and consequently the reduced part of the curler may be slidably moved within the bore of the expanded part until the flared end 55 strikes the depending stop lug 58 and in such relation only a small portion of the restricted part of the curler extends or projects beyond the dome shaped portion and if it is desired to withdraw the restricted part, the projecting portion is grasped, and pulled outwardly until the inner flared portion strikes the dome 51' at which time the restricted part is slightly rotated to interlock with the outer tube.

Since many changes can be made in the above methods of operation and many apparently widely different embodiments of the invention could be devised without departing from the scope thereof, it is intended that all matter contained in the above description and shown in the accompanying drawing should be interpreted as illustrative and not in a limiting sense.

I claim:

1. A hair curler of the character described comprising superimposed hingedly associated sections constituting an expanded part and a reduced part, and spring means for normally holding said expanded part open and said reduced part closed, said expanded part having means for gripping a portion of a tress of hair, said reduced part constituting manipulatable means for winding the hair gripped by said expanded part thereabout, said reduced part having means for gripping a portion of a tress of hair, said expanded part constituting manipulatable means for winding the hair gripped by said reduced part about the latter.

2. A hair curler of the character described comprising superimposed sections defining a split expanded part and a split reduced part, means pivotally sustaining said sections, and a spring for holding one of said parts normally closed and the other part normally open, said open part adapted to grip a portion of a tress of hair, said closed part constituting manipulatable means for winding said tress about said open part.

3. A hair curler of the character described comprising superimposed and juxtaposed hollow sections defining a split expanded part and a split reduced part, fulcrum means hingedly interconnecting said sections, a spring for holding the sections of said expanded part separated to define an elongated gap adapted to receive a part of a tress of hair, said spring cooperating with said expanded part to hold said reduced part closed to define a handle adapted to be rotated for coiling said tress about said expanded part.

4. A hair curler of the character described comprising superimposed sections defining a split expanded part and a split reduced part, means pivotally sustaining said members, a spring for holding one of said parts normally closed and the other part normally open, said closed part adapted to be opened upon actuation of said expanded part for anchoring a part of a tress of hair, said expanded part constituting manipulatable means for winding the tress of hair anchored by said open reduced part thereabout.

5. A hair curler of the character described comprising superimposed, juxtaposed, and elongated hollow sections defining a split expanded part and a split reduced part, fulcrum means

hingedly interconnecting said sections, a spring for holding the sections defining said reduced part closed, said expanded part adapted to be actuated to open said closed part to anchor a portion of a tress of hair, said expanded part defining a handle adapted to be rotated for coiling said tress about said reduced part.

6. A hair curler of the character described comprising superimposed sections defining a split expanded part and a split reduced part, means pivotally sustaining said sections, a spring for holding one of said parts normally closed and the other part normally open, said open part adapted to grip a portion of a tress of hair, said closed part constituting manipulatable means for winding said tress about said open part, said open part adapted to be closed against the resistance of said spring to open said closed part to permit the insertion of a tress of hair in the latter, said spring cooperating to hold said opened reduced part against the inserted tress to grip the latter, said expanded part constituting a handle adapted to be rotated for winding the gripped hair in said reduced part about the latter.

7. A hair curler of the character described comprising superimposed and juxtaposed hollow sections defining a split expanded part and a split reduced part, fulcrum means hingedly interconnecting said sections, a spring for holding the section to said expanded part separated to define an elongated gap adapted to receive and grip a part of a tress of hair inserted therein, said reduced part constituting a handle adapted to be rotated for winding the gripped hair about said expanded part, the sections of said expanded part adapted to be moved towards each other against the resistance of said spring to diverge said sections defining said reduced part to permit the insertion of a tress of hair therein, said spring cooperating with the sections of said expanded part to move the sections of the reduced part towards each other to grip the tress inserted therein, the sections of the expanded part constituting a handle adapted to be rotated for winding the tress gripped by said reduced part thereabout.

8. A hair curler of the character described comprising superimposed elongated sections defining a split expanded part and a split reduced part, means pivotally sustaining said members, a spring for holding said reduced part normally closed and the expanded part normally open, said closed part adapted to be opened upon manipulation of said expanded part to grip a portion of a tress of hair, said expanded part constituting manipulatable means for winding said tress about said reduced part.

9. A hair curler of the character described comprising juxtaposed and elongated hollow U shaped sections defining an expanded part and an aligned reduced part, a fulcrum pin hingedly interconnecting said sections, a spring for holding the sections of said expanded part separated to define an elongated gap adapted to receive a part of a tress of hair, said spring cooperating with spaced portions of expanded part to hold said reduced part in abutting relation to define a handle adapted to be rotated for coiling said tress about said expanded part.

10. A compound hair curler comprising complementary U shaped sections having their channels facing towards each other to define a longitudinally disposed bore, said sections comprising superimposed enlarged portions and restricted portions, said enlarged portions constituting an expanded part, said restricted portions con-

stituting a reduced part, fulcrum means pivotally interconnecting said sections, and a spring for holding said enlarged portions separated and said restricted portions closed to permit the insertion of a portion of a tress in said expanded part to be coiled about the latter upon rotation of said reduced part.

11. A compound hair curler comprising complementary U shaped sections having their channels facing towards each other to define a longitudinally disposed bore, said sections comprising superimposed enlarged portions and restricted portions, said enlarged portions constituting an expanded part, said restricted portions constituting a reduced part, fulcrum means pivotally interconnecting said sections, and a spring for holding said enlarged portions separated and said restricted portions closed, said enlarged portions adapted to grip a tress of hair and said restricted portions constituting a handle adapted to be rotated for winding the tress gripped by said enlarged portion thereabout.

12. A compound hair curler comprising complementary U shaped sections having their channels facing towards each other to define a longitudinally disposed bore, said sections comprising superimposed enlarged portions and restricted portions, said enlarged portions constituting an expanded part, said restricted portions constituting a reduced part, fulcrum means pivotally interconnecting said sections, and a spring for holding said enlarged portions separated, and said restricted portions closed, said restricted portions upon separation thereof upon actuation of said enlarged portions adapted to grip a tress of hair and said expanded part serving as manipulatable means for winding the tress of hair gripped by said restricted portions and thereabout.

13. A hair curler comprising a tube having an enlarged and restricted portion, a cover mounted on said tube and comprising an enlarged and restricted portion, fulcrum means carried by said tube for pivotally supporting said cover, spring means for normally holding said restricted portions in abutting relation and said enlarged portions separated.

14. A hair curler comprising a tube having an enlarged and restricted portion, a cover mounted on said tube and comprising an enlarged and restricted portion, fulcrum means carried by said tube for pivotally supporting said cover, spring means for normally holding said restricted portions closed and said enlarged portions separated, said separated enlarged portions defining anchoring means for receiving and gripping a tress of hair, said closed restricted portions defining a handle adapted to be rotated for winding the tress gripped by said enlarged portions.

15. A hair curler comprising a tube having an enlarged and restricted portion, a cover mounted on said tube and comprising an enlarged and restricted portion, fulcrum means carried by said tube for pivotally supporting said cover, spring means for normally holding said restricted portions closed and said enlarged portions separated, said separated enlarged portions adapted to be moved towards each other to open said closed restricted portions to define anchoring means to grip a tress of hair, said enlarged portions constituting a handle adapted to be rotated for winding the tress gripped by said restricted portions thereabout.
